ATTORNEY

UNITED STATES PATENT OFFICE

IRA T. FISK, OF NORTH HOOSICK, NEW YORK, ASSIGNOR TO STEVENS & THOMPSON PAPER COMPANY, OF NORTH HOOSICK, NEW YORK, A CORPORATION OF NEW YORK

IMPRINT DEVICE

Application filed January 19, 1929. Serial No. 333,679.

My invention relates to devices for imprinting papers with so called water marks, and while suitable for marking any kind of paper, it is particularly adapted and designed for the marking of creped tissue such as that used for toilet papers and towels.

It has heretofore been difficult, if not impossible, to satisfactorily water mark a creped paper because in the drying process the mark becomes indistinct or is entirely obliterated. In the ordinary method of marking papers, the paper web is uniformly heated, or if not heated is at least of uniform temperature, throughout, and it has been sought to obtain the desired mark by the mere application of pressure over limited areas. This has been accomplished by means of a marking roll which is held in contact under substantial pressure with a platen roll and between which said rolls the paper runs. Sometimes both of the rolls are "cold" and sometimes one of the hot drying rolls is utilized as a platen roll. In either case the web of paper is of substantially uniform temperature throughout.

According to my method those limited areas of paper which form the design itself are heated to a much higher degree than the surrounding areas and hence are dried at a much higher rate. In addition to heating only the limited areas of the paper web which carry the design I also apply pressure to these areas so that the design is practically ironed into the paper and dried.

The objects of my invention are to provide a marking device and a method of procedure whereby it is possible to satisfactorily apply a so called "water mark" to any kind of paper and particularly to creped tissues such as towels, toilet papers and the like, whereby a distinct and clearly apparent mark is produced upon or in the finished paper. Another object of my invention is to provide a method of procedure and a means whereby this marking may be done at a comparatively high speed so that the paper may be marked as it passes through the ordinary paper making machine at the usual speed.

With these objects in view my invention

includes the method of procedure and the means described below and illustrated in the accompanying drawings, in which—

Fig. 1 is a diagrammatic side elevation view of a portion of a paper making machine 55 showing my marking device and several of the drying rolls near the wet end of the machine;

Fig. 2 is an enlarged detailed side elevation view of my device; and

Fig. 3 is an elevation view of the marking roll.

Referring to the drawings, 1 represents the ordinary dryer rolls; 2 is the upper dryer felt and 3 the lower dryer felt. 4 represents the felt rolls and 5 represents the paper web which is travelling in the direction of the arrow indicated in Fig. 1.

Mounted in a convenient place upon the frame, 6, of the paper machine is the bearing, 7, in which is journaled the marking roll, 8. This roll is provided with a design in relief such, for example as shown at 9, and which should be 0.075 inches or more above the general surface of the roll. The marking roll is hollow and is provided with caps, 10, at each end of the hollow shaft through which lead steam pipes, 11 and 12. Steam is passed through the cylinder in the same way as through the dryer rolls and it is thus heated so to a substantial degree.

A platen roll, 13, over which may pass the upper felt, 2, is journaled in the arm, 14, which in turn, is pivoted to the support, 15, at point, 16. The free end of this arm, 14, 85 carries a weight, 17, designed to yieldingly force the platen roll toward the marking roll under some considerable pressure. From the drawings it will be apparent that the upper dryer felt runs between the platen roll and the marking roll.

The web of paper, 5, after leaving the last press rolls (not shown), is conducted around the roll, 18, and thence upwardly and around the marking roll, 8, and downwardly to the dryers. The paper runs in contact with the marking roll and lies beneath the dryer felt, 2, which runs between the marking and platen rolls.

I prefer to arrange the marking roll in 100

about the position shown so that the web of paper extends a considerable distance around the surface thereof. In other words, it is desirable to hold the paper in contact with the heated design on the marking roll as long as possible, and for this reason, where the paper speed is high, the marking roll should be of comparatively large diameter.

At the press rolls, the paper is creped and is then led into the marking device, as shown in Figs. 1 and 2. Here, the creped paper comes in contact only with the raised or relief portions of the design, and since these portions are highly heated, it is apparent that limited areas only of the creped paper which conform to the design on the marking roll are heated to a higher degree than the surrounding areas. Moreover, as the paper passes into the bite between the marking and platen rolls, the areas in contact with the relief portions of the design are not only heated but are also highly compressed against the felt so that considerable moisture is absorbed therefrom. After leaving the bite between the rolls, the web of paper continues around the marking roll but is not generally in contact therewith; it being only in contact with the relief or raised portions of the design thereon. In this way heat is applied to those limited areas of the paper web which comprise the design, and for a comparatively long time, depending upon the speed and diameter of the marking roll. In this way it will be apparent that these particular areas are dried at a rate which is much faster than the drying of those areas of the paper which immediately surround the design. In this way the design is permanently ironed into the paper and is not destroyed by the subsequent passage of the paper around the drying rolls.

When one of the dryer rolls is used as a platen, as heretofore, it will be apparent that the entire web of paper being in contact with the surface thereof will be uniformly dried throughout. With my arrangement, the design portion is dried at a much higher rate than the other portion thus giving permanence thereto.

While I have described my invention as particularly adapted for the marking of a creped paper (because great difficulty has heretofore been encountered in the successful marking of such papers), it is obvious that my device is not limited to such applications but may be used for any paper. Hence it is to be understood that the words which I have used in describing my invention are words of description rather than of limitation, and that changes within the purview of the appended claims may be made without departing from the true scope and spirit thereof in their broader aspects.

What I claim is—

65. 1. In a paper making machine, the combination with a marking roll, of means for heating said roll, a platen roll, and a dryer felt running between said rolls adapted to convey the paper into contact with the marking roll.

2. In a paper making machine, the combination with a marking roll, of means for heating said roll, a platen roll, a dryer felt running over said marking roll, and means for yieldingly compressing the felt between said rolls.

3. In a paper making machine, the combination with a marking roll, of means for heating said roll, a platen roll, and means for conducting the paper web between the marking and platen roll.

4. A device of the character described for marking a web of paper and comprising a heated marking roll around which the paper runs, a dryer felt running around said roll and adapted to maintain the paper in contact therewith, a platen roll, and means for yieldingly compressing the felt and paper between said rolls.

5. In a paper making machine including a plurality of dryer rolls, a device for marking the paper comprising a heated marking roll having a design in relief thereon and around which the paper runs before reaching the dryer rolls, means for yieldingly compressing the paper against the marking roll, and means for drying those limited areas of the paper which carry the imprint of the relief part of the design at a faster rate than the surrounding areas.

6. The process of watermarking paper which comprises substantially compressing a wet web thereof over limited areas to form the desired water mark, and momentarily maintaining said limited areas at a higher temperature than the surrounding areas to effect a relatively quicker drying thereof.

7. The process of watermarking paper which comprises momentarily applying heat to limited areas of a wet web thereof conforming to the desired design, and thereafter compressing said limited areas to a substantial degree while continuing the heating thereof; whereby said areas are dried at a faster rate than the surrounding areas.

8. The process of watermarking paper which comprises momentarily heating limited areas thereof conforming to the desired design, compressing said limited areas to a substantial degree during the heating thereof, and thereafter momentarily maintaining said compressed areas at a higher temperature than the surrounding areas; whereby said compressed areas are rendered comparatively dry.

9. The process of watermarking paper which comprises momentarily compressing limited areas thereof conforming to the desired design, and simultaneously heating said limited areas to a higher degree than the

surrounding areas and partially absorbing the moisture therefrom.

10. In a paper marking device of the character described, the combination with a marking roll, of means for heating said roll, a platen roll, a belt of absorbent material between said rolls and means for compressing the paper between the marking roll and belt.
11. In a device of the character described, the combination with a platen roll, of a heated marking roll coating therewith, and means for retaining a web of paper in contact with said marking roll over a substantial portion of its periphery.
15. 12. In a device of the character described, the combination with a platen roll, of a heated marking roll coating therewith, and means for retaining a web of paper in contact with said marking roll over a substantial portion of its periphery before passing between said rolls.
20. 13. In a device of the character described, the combination with a platen roll, of a heated marking roll coating therewith, and means for retaining a web of paper in contact with said marking roll over a substantial portion of its periphery after passing between said rolls.
25. 14. In a paper making machine, the combination with a platen roll, of a heated marking roll coating therewith, and a web of paper passing between said rolls and having close contact with the marking roll over a substantial portion of its periphery.
30. 15. In a paper making machine, the combination with a platen roll, of a heated marking roll of comparatively large diameter coating with said platen roll, and a web of paper passing between said rolls and having close contact with the marking roll over a substantial portion of its periphery.
35. 16. In a paper making machine, the combination with a platen roll, of a heated marking roll coating therewith, a web of paper passing between said rolls and having close contact with the marking roll over a substantial portion of its periphery, and means for yieldingly compressing the paper between said rolls.
40. 17. That step in the marking of paper which consists in applying a higher degree of heat to the portions of a wet web thereof conforming to the desired design than to the portions surrounding said design.
45. 18. In a paper marking device, the combination with a heated marking roll, of a belt of absorbent material running around said roll and adapted to retain a wet web of paper in contact with said roll over a substantial portion of its periphery.

IRA T. FISK.
